US0D1002406S

(12) **United States Design Patent** (10) **Patent No.:** **US D1,002,406 S**
(45) **Date of Patent:** **** Oct. 24, 2023**

(54) **BATTERY TESTING APPARATUS**

(71) Applicant: **Hunan Lianke Technology Co., Ltd,**
Hunan (CN)

(72) Inventors: **Ke Lou**, Hunan (CN); **Zhenbin Zhou**,
Hunan (CN); **Kaijun Zhou**, Hunan (CN); **Changgang Zhang**, Hunan (CN)

(**) Term: **15 Years**

(21) Appl. No.: **29/802,514**

(22) Filed: **Aug. 5, 2021**

(30) **Foreign Application Priority Data**

May 19, 2021 (CN) 202130301665.7

(57) **CLAIM**

The ornamental design for a battery testing apparatus, as shown and described.

DESCRIPTION

FIG. 1 is a perspective view of a battery testing apparatus showing our new design;

FIG. 2 is a front elevation view thereof;

FIG. 3 is a rear elevation view thereof;

FIG. 4 is a left elevation view thereof;

FIG. 5 is a right elevation view thereof;

FIG. 6 is an enlarged top plan view thereof; and,

FIG. 7 is an enlarged bottom plan view thereof.

The broken lines shown in the figures depict portions of the battery testing apparatus that form no part of the claimed design.

1 Claim, 6 Drawing Sheets
